UNITED STATES PATENT OFFICE.

CHARLES H. GIFFORD, OF ATTLEBORO, MASSACHUSETTS.

PIN AND THE LIKE.

No. 893,237.

Specification of Letters Patent.

Patented July 14, 1908.

Application filed January 23, 1908. Serial No. 412,274.

To all whom it may concern:

Be it known that I, CHARLES H. GIFFORD, a citizen of the United States, residing at the town of Attleboro, in the county of Bristol and State of Massachusetts, have invented certain new and useful Improvements in Pins and the Like, of which the following is a specification, reference being had therein to the accompanying drawing.

10 This invention relates to pins, buttons and the like, and has for its object to provide a simple and effective means whereby a strong and durable, yet very inexpensive pin or button, having a thin shell of precious or 15 other metal, may be constructed.

This pin is made of a heavy body portion or supporting core to which the attaching means may be connected. This core is then provided with a covering or shell having a 20 comparatively thin back plate, and an extremely thin front plate, and the edge of the former is rolled over that of the latter.

In ordinary pins the construction is the reverse to the present form, that is, the front 25 plate is rolled over the back plate and it is found necessary to make the front plate of considerable thickness in order that it shall be strong or stiff enough to hold the parts together in a practical manner, and when this 30 front plate is made of solid gold it is necessarily expensive on account of this extra thickness of stock required to be rolled and retain the parts.

By my improved construction of rolling 35 the back over the front I am enabled to make the front plate of solid gold almost as thin as paper, and yet on account of its figured face and crowning form it possesses sufficient strength and durability to serve its purpose 40 in a practical manner. The back plate, which may be of a cheaper grade of material, must be considerably heavier in order to be rolled and hold the parts together.

Another and essential feature of this construction is that the parts receiving the most 45 strain are strong and heavy, as in the case of a cuff pin the core or central body portion is formed of a less expensive material, such as brass, or the like, with the joint and catch 50 stamped out or formed integral therewith, preferably by drawing or forcing the stock from the inner side outward near either end thereof, forming substantially cup-shaped portions, the joint cup having its bottom end 55 removed to receive the eye of the pin-tongue,

while the catch cup is slotted at its side to receive the point of the pin-tongue. A pin of this character may be constructed with great strength where strength is necessary and entirely covered with a thin shell of precious metal rendering the same handsome and attractive, strong and durable, and at the same time reducing the cost to a minimum.

With these and other objects in view, the invention consists of certain novel features of construction, as will be more fully described and particularly pointed out in the appended claims.

In the accompanying drawings: Figure 1—is a perspective view showing a cuff pin of my improved construction. Fig. 2—is a central longitudinal sectional view illustrating the construction of my improved pin. Fig. 3—is a detail showing the back plate struck up into a cup form having an aperture at either end through which the outwardly projecting catch and joint members of the supporting core extend. Fig. 4—illustrates the heavy supporting core member with its raised joint and catch members integral therewith. Fig. 5—is a transverse section through the catch portion on line 5—5 of Fig. 2. Fig. 6—is a transverse section through the joint on line 6—6 of Fig. 2. Fig. 7—is a modification illustrating my improved construction of rolling the back plate or binding member over the front as applied to a hat-pin. Fig. 8—illustrates the back plate or binding member of the hat-pin drawn up into a cup-form with its center portion removed through which center portion the base of the pin stem may be attached to the core. Fig. 9—is another modification showing a binding rim or member surrounding the edge of the core or body portion, the same being rolled over the back of the body for the purpose of holding the front plate in position thereon.

Referring to the drawings, at 1 is the core which may be made in a form to correspond to the style of pin desired. When that style known as a beauty or cuff-pin is to be made, this core is preferably formed of a comparatively thick or heavy metal necessary for giving the pin the required strength and rigidity. As the joint and catch are the portions which require considerable strength it is found particularly advantageous to form them integral with the heavy core. In this particular case I form both the joint member 2 and the catch member 3 by forcing or draw-

ing the stock from the back of the plate outward into a rectangular cup-shape. The bottom portion or outer end of the joint portion being cut away or removed so that the 5 joint end or eye 4 of the pin-tongue 5 may be passed or inserted therein. In order to hold the pin tongue in position in this cup member a pivot may be passed therethrough and riveted in both side walls 6 and 7 of the joint 10 member in the usual way, or the sides of the walls may be forced inward, if desired, as at 8 and 9, into the eye of the pin see Fig. 6 forming a trunnion on which the same may rotate. The upper edge of the forward wall 10 of this cup member serves as the fulcrum on 15 which the lower side of the pin may rest just before its point enters the catch member. The cup-shaped catch member at the opposite end of this core is cut away at its front 20 edge 11 and also on its side at 12 forming a recess or hook into which the point of the pin-tongue 5 may be inserted. By this construction it will be seen that this joint and catch have great strength, the joint in particular, 25 which is obliged to withstand the greatest strains, is formed with four integral walls all adapted to support each other and rendering it almost impossible to be bent or otherwise destroyed. I do not confine myself to making 30 this joint and catch integral with the core member as either one or both may be formed independently and secured to said core.

It is found in practice in the construction of pins of this character very desirable to ornament the front faces with handsome designs and in order to produce this result in the most effective manner it is advantageous to have this front plate made of as thin material as possible.

40 By my improved construction, which is obtained by rolling the edge of the back plate over that of the front, enables me to use a stock extremely thin, thereby obtaining numerous advantages, among others being that the 45 ornaments stamped or embossed thereon are clean cut even when the designs embody the finest detail. Then again, by using a thin stock for this front it may be made of solid gold and at the same time, on account of its lightness in weight, its cost is 50 reduced to the minimum. This front plate 13 formed in the manner above described is preferably made in a crowning shape and with an outwardly extending ridge or flange 55 14 around it where it sets against the face of the core.

The back plate 15 is preferably struck up into a cup-shape, as best illustrated in Fig. 3, and made of a lower grade of gold than that 60 of the front plate. It is also made of a greater thickness or of a thickness adapted to be rolled and be of sufficient strength to retain the parts in position. The bottom of this cup member is provided at either end 65 with recesses 16 and 17 adapted to fit over

the outwardly projecting joint and catch members 2 and 3. The upper edge of this cup-member is then rolled over the outwardly extending flange 14 of the front shell and a solid gold shell pin is produced of the 70 strongest possible construction and of the minimum expense.

I do not confine myself to any particular style of pin as any article of jewelry of this general style and construction, such as cuff-pins, brooches, hat-pins, cuff-buttons and the like, may be made by my improved construction. Neither do I limit myself to forming the same of any particular material, the greatest advantage, however, being gained where 75 the shell is made of the more expensive or precious metals. A hat-pin or cuff-button of my improved construction may be formed in the manner best illustrated in Figs. 7 and 8, in which the core or body portion 18 is 80 blanked out in the desired shape. The front plate 19 is formed of thin stock having an outwardly extending flange 20 which engages the front face of said core. The back plate or binding member 21, as best illustrated in Fig. 8, is made of slightly thicker material and stamped out in a cup-shape with its center portion 22 cut away. The abutting end 24 of the pin-stem or shank 25 is secured to the center core or body portion. 85 The member 21 is then placed in position entirely covering the remaining portion of the core or body member and its upper edge is turned over or rolled onto the extending edge of the front plate thus forming a very neat, 90 strong and inexpensive hat-pin, button or the like, having a solid gold shell.

I do not confine myself, however, to rolling the back plate over the front plate as this back plate may be operated in the reverse 95 manner as illustrated in Fig. 9 which would be to form the hole 22, see Fig. 8, a little larger leaving only a narrow rim and then pass the same down over the front plate and roll the edge 20 on the underside of the core 100 or body portion, thus firmly binding the front plate in position.

Having thus described my invention, what I claim as new and desire to secure by Letters Patent, is:

1. An article of jewelry comprising a stiffening or supporting middle member, joint and catch members connected to said supporting member, a front plate of very thin material, and a third member rolled 115 over the edges of said front and supporting members to secure the same together, and a pin-tongue adapted to be held by said joint and catch members.

2. A new article of jewelry comprising a 125 stiffening or supporting middle member, joint and catch members connected to said supporting member, a front plate of very thin material, a back plate having its edges rolled over that of the front plate whereby 130

the whole is secured together, and a pin-tongue adapted to be held in said joint and catch members.

3. An article of jewelry comprising a stiffening or supporting middle member, joint and catch members formed integral with said supporting member, a front plate of very thin material, and a third member engaging the edges of said front plate and supporting member to secure the same together, and a pin-tongue adapted to be held by said joint and catch members.

4. A new article of jewelry comprising a stiffening or supporting middle member, joint and catch members formed integral with said supporting member, a front plate of very thin material, a back plate having its edges rolled over that of the front plate whereby the whole is secured together, and a pin-tongue adapted to be held in said joint and catch members.

5. An article of jewelry comprising a stiffening or supporting core, joint and catch members attached to said core, a front plate of very thin material surrounded by an outwardly extending flange adapted to rest upon the face of said core, and a back plate of thicker material drawn up to receive said core and having its edge rolled over the said flange of the front plate binding the same to the core whereby all of the members are secured together, and a pin-tongue pivoted in said joint member.

6. A pin, comprising a stiffening core, joint and catch members formed integral with said core, a front plate, a back plate drawn up into a cup-shape to receive said core and having its edge rolled over that of the front plate whereby the whole is secured together, said back plate being provided with apertures through which said joint and catch members project, and a pin-tongue adapted to be held in said members.

7. A pin comprising a stiffening core, joint and catch members supported on said core, a shell comprising a front plate, a back

plate drawn up into a cup-shape to receive said core and having its edge rolled over that of the front plate whereby the whole is secured together, said back plate being provided with apertures through which said joint and catch members project, and a pin-tongue pivoted in said joint member the point of said pin being adapted to engage said catch member.

8. A pin comprising a stiffening core, joint and catch members drawn up out of the stock of said core each into substantially a cup-shape, a shell comprising a front plate of very thin material, a back plate of thicker material drawn up into a cup-shape to receive said core and having its edge rolled over that of the front plate whereby the whole is secured together, said back plate being provided with apertures through which said joint and catch members project, and a pin-tongue pivoted in said joint member, 65

one wall of said joint member forming a fulcrum therefor, the point of said pin being adapted to engage said catch member.

9. A pin comprising a stiffening core, joint and catch members supported on said core, a shell comprising a front plate of very thin material surrounded by an outwardly extending flange adapted to rest upon the front face of said core, a back plate drawn up into substantially a cup-shape to receive said core and having its edge rolled over the flange of said front plate binding the same to the core whereby all the members are secured together, said back plate being provided with apertures through which said joint and catch members project, and a pin-tongue pivoted in said joint member the point of said pin being adapted to engage 85

said catch member.

In testimony whereof I affix my signature in presence of two witnesses.

CHARLES H. GIFFORD.
